SNAP VALVE COUPLING

Charles O. Wilson, Muskegon, Mich.

Application January 22, 1934, Serial No. 707,670

3 Claims. (Cl. 137—13)

The present invention relates to snap valve couplings and more particularly to sprinkler head couplings adapting the sprinkler head for ready and convenient attachment to fixed water supply pipes of underground irrigation systems.

The principal objects of the invention are to provide a quickly detachable coupling whereby a portable sprinkler head may be readily attached to any of a plurality of spaced valved water outlets whose upper ends are flush with the surface area to be watered; to provide such a coupling whose portable sprinkler head is provided with a manually controlled lever for operating the normally closed valve of the fixed 10 water outlet; to provide a coupling having a fixed water outlet provided with a swingable cover for protecting the water outlet and its valve which when in its closed position is flush with the surface area; to provide a valved water outlet whose 20 valve cannot be opened except by a manually controlled lever associated with the sprinkler head when the sprinkler head is detachably secured to its fixed water outlet; and, to provide a quickly detachable coupling of the character 25 above indicated which is simple in construction, economical in manufacture and efficient in use.

An illustrative embodiment of the invention is shown in the accompanying drawings, wherein:

Figure 1 is an elevational view of the valved coupling;

Figure 2 is an elevational view of the valved water outlet portion of the coupling, showing its swingable cover in closed position and flush with the surface area when not in use;

Figure 3 is a perspective view of the valved water outlet portion of the coupling showing its swingable cover in open position and ready to detachably receive the sprinkler head portion of the coupling;

Figure 4 is a perspective view of the underground water supply system and its several valved water outlets flush with the surface area to be watered, a conventional type sprinkler head being shown for detachable connection with any of the several water outlets;

Figure 5 is a sectional view on line 5—5 of Figure 6;

Figure 6 is a central longitudinal sectional view on line 6—6 of Figure 7 but showing the manually operated lever controlled cam out of valve opening position;

Figure 7 is a sectional view on line 7—7 of Figure 6 but showing the manually operated lever controlled cam depressing the valve plunger to valve opening position; and

Figure 8 is a fragmentary sectional view of the valved water outlet and its swinging cover in closed position.

Referring to the drawings in which like parts of the structure shown are designated by the same numerals in the several views, the sprinkler head coupling generally comprises a tubular water outlet 10 adapted for vertical and underground installation secured to an underground water lead conduit 11 in any suitable manner as 5 by the screw threads shown and whose port 12 is closed by the pivoted swinging cover 13 which is substantially flush with the surface area 14 when the swinging cover is closed as best shown in Figure 1.

This water outlet is provided with a plurality of spaced inwardly radially projecting lugs 15 and has a resilient annular collar 16 of rubber or the like disposed within an annular recess 17 circumscribing its port 12 and spaced from the 20 lugs 15. A valve comprising a pair of discs 18, 19 respectively of metal and of some resilient material such as rubber or the like are disposed within the vertical bore 18 of the water outlet and are secured transversely and medially of a 25 reciprocable plunger 20 whose lower end is adapted to reciprocate in the bore 21 of the collar 22 which forms a bearing for the plunger. A coiled expansion spring 23 embracing the lower end 30 of the plunger and interposed between the collar 22 and disc 18 normally maintains the resilient disc element 19 against the valve seat 24 to thus close the valve.

A sprinkler head 25 provided at its upper end with a plurality of conventional laterally disposed conduits 26 is connected to a tubular base member 27 whose lower end is provided with a resilient collar 28 disposed within an annular recess 29. The lower end of the base member 27 has a plurality of spaced outwardly radially projecting lugs 30 which interlockingly register with the lugs 15 of the water outlet 10 adapting the sprinkler head 25 to be rotatably detachably coupled axially in aligned communicating relation with the water outlet 10 and with the two resilient collars 16, 28 in compressed leak-proof contact as best shown in Figures 6 and 7. The annular recesses 17 and 29 of the water outlet and sprinkler head are formed by inwardly projecting annular walls and the resilient washer 50 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960

as the lugs of the sprinkler head. The lower wall of the annular recess 17 of the water outlet constitutes a valve seat for the valve which operates between the valve seat and the guide formed by the fixed collar 22.

5 A cam element 38 operatively associated with the head of the plunger 20 and disposed within the bore of the base member of the sprinkler head 25 is rigidly secured medially of the shaft 32 rotatable in its bearings 33, 34 and a manually operable lever 35 is secured to the outwardly projecting end of the shaft 32 for effecting rotation of the shaft.

10 As heretofore suggested, the surface area which it is desired to water, is provided with a plurality of spaced water outlets 10 which are connected to underground conduits 11 as indicated in Figure 4. The valves of these spaced water outlets 10 are normally closed and when it is desired to 15 water the area surrounding a particular water outlet, the sprinkler head 25 is detachably secured thereto as heretofore described. By the manual turning of the lever 35 the cam element 38 depresses the plunger 20 from the position shown 20 in Figure 6 to the position shown in Figure 7 to open the valve.

25 While but one specific embodiment of the invention has been herein shown and described, it will be understood that numerous details of the 30 construction shown may be altered or omitted without departing from the spirit of this invention as defined by the following claims.

I claim:

1. In a structure of the class described, a water outlet having a plurality of spaced radially projecting internal lugs, a sprinkler head having a plurality of spaced radially projecting external lugs interlockingly registering with said other lugs and adapting the sprinkler head to be 35 detachably axially coupled with the water outlet, a resilient collar carried by the sprinkler head and projecting below the lugs thereof, a resilient washer located within the water outlet and cooperating with the resilient collar to form a 40 water-tight joint, means carried by the water outlet for interlocking the resilient washer with 45

the water outlet, a portion of said means forming a valve seat, a valve within the water outlet co-operating with the said valve seat, and valve operating means carried by the sprinkler head.

2. In a structure of the class described, a water outlet having a plurality of spaced radially projecting internal lugs, a sprinkler head having a plurality of spaced radially projecting external lugs interlockingly registering with said other lugs and adapting the sprinkler head to be detachably axially coupled with the water outlet, a resilient collar carried by the sprinkler head and projecting below the lugs thereof, a resilient washer located within the water outlet and co-operating with the resilient collar to form a water-tight joint, means carried by the water outlet for interlocking the resilient washer with the water outlet, said means including a lower annular wall forming a valve seat below the washer, a valve within the water outlet cooperating with the said valve seat, and valve operating means carried by the sprinkler head.

3. In a structure of the class described, a water outlet having a plurality of spaced radially projecting internal lugs, a sprinkler head having a plurality of spaced radially projecting external lugs interlockingly registering with said other lugs and adapting the sprinkler head to be detachably axially coupled with the water outlet, a resilient collar carried by the sprinkler head and projecting below the lugs thereof, a resilient washer located within the water outlet and co-operating with the resilient collar to form a water-tight joint, means carried by the water outlet for interlocking the resilient washer with the water outlet, a portion of said means forming a valve seat, a fixed guide located below and in spaced relation with the valve seat, a plunger slidable in the fixed guide and extending through the resilient washer and the resilient collar, a valve carried by the plunger and operating between the guide and the valve seat to cooperate with the latter, and valve operating means carried by the sprinkler head.

45

CHARLES O. WILSON.
